CLAIM

The ornamental design for a hollow-carved watchband, as shown and described.

DESCRIPTION

FIG. 1 is a front perspective view of my new design for a hollow-carved watchband;

FIG. 2 is a front view thereof;

FIG. 3 is a rear view thereof;

FIG. 4 is a left side view thereof;

FIG. 5 is a right side view thereof;

FIG. 6 is an enlarged top view thereof;

FIG. 7 is an enlarged bottom view thereof;

FIG. 8 is an enlarged view of a portion of FIG. 2;

FIG. 9 is an enlarged view of a portion of FIG. 6;

FIG. 10 is an enlarged view of a portion of FIG. 6;

FIG. 11 is an enlarged view of a portion of FIG. 7; and,

FIG. 12 is an enlarged view of a portion of FIG. 7.

The broken lines in FIGS. 2 and 6-12 depict partial view indicia and form no part of the claimed design. The portions of the hollow-carved watchband shown in broken line form no part of the claimed design.

1 Claim, 12 Drawing Sheets
